PROTRACTOR

Warren B. Weyrick, Akron, Ohio

Application March 29, 1945, Serial No. 585,534

4 Claims. (Cl. 33—75)

1

This invention relates to protractors.

An object of the invention is to provide an improved protractor of simple compact construction and by which readings of angles may be readily made with optimum accuracy.

Another object of the invention is to provide a protractor of the character described which will accurately measure both inside and outside angles.

These and other objects of the invention will be manifest from the following brief description and the accompanying drawings.

Of the accompanying drawings:

Figure 1 is a front elevational view of a protractor embodying the invention.

Figure 2 is a side elevation thereof as viewed from the right of Figure 1.

Figure 3 is a view similar to Figure 1, but illustrating the protractor in another position of use for measuring an angle.

Figure 4 is a view similar to Figure 1 illustrating a modified form of the invention.

Figure 5 is an enlarged cross-section taken substantially on line 5—5 of Figure 4.

Figure 6 is a view similar to Figure 1 illustrating another modified form of the invention.

Figure 7 is a fragmentary view of the device shown in Figure 1, illustrating still another modified form of the invention.

Referring particularly to Figures 1, 2 and 3 of the drawings the numeral 10 designates a generally rectangular plate, of substantial width, and having straight side edges 11 and 12 in parallelism. Pivot at 13 to plate 10, in superposed relation thereto, may be a relatively small plate or member 14, the pivot being closely adjacent one end of plate 10 and equidistant from side edges 11 and 12 thereof.

Plate 14 is provided, outwardly of pivot 13, with a straight-edged portion 15 which forms an outside angle with one side edge 11 and which may be of length substantially equal to the width of plate 10, as shown. The lateral end of plate 14 adjacent said side edge 11 may be rounded as shown so as not to project beyond a radius from pivot 13 equal to the distance from the pivot to the side edge. Plate 14 may have the other lateral end thereof extended to provide a straight-edged portion 16 which projects outwardly of straight side edge 12 a substantial distance, this straight edge 16 being in parallelism with edge 15 and forming an inside angle with said side edge 12. The edges 11 and 12 of plate 10 and edges 15 and 16 of member 14, respectively, being in parallelism it will be seen that all angles

2

which edge portions 12 and 16 make with each other, as member 14 is pivoted relatively of plate 10, will be equal to corresponding angles formed between edge portions 11 and 15. The pivot end of plate 10 is cut back at angles from a radius about pivot 13, as indicated at 10b and 10c, so that the plate will not project beyond straight-edged portion 15 in any angular position of adjustment of plate 10 and member 14. The edge portions 15 and 16 of plate 14 preferably are substantially close to pivot 13 for compactness and simplicity of design.

The member 14 may be shaped to provide a narrow indicator or finger 20 which extends longitudinally of plate 10 to adjacent the end thereof opposite to pivot 13, the free end of this indicator having a mark 21 or other means thereon for indicating, on a scale 22 marked on plate 10, the various angles between adjacent straight edged portions, as previously described. The indicator, as shown in Figure 1, is set to read zero when the straight edged portions are at right angles to each other, and the scale is marked to indicate angles within a range of ninety degrees plus or minus fifteen degrees, this range being satisfactory for a maximum of practical uses of the device, as by mechanics, engineers, draftsmen, inspectors, checkers and many other skilled craftsmen. It will be seen however, that the range of readings may be increased, but possibly at the expense of increasing the proportions of the device. To obtain maximum range of degrees on the scale 22 the zero mark is equidistant from side edges 11 and 12 of plate 10, that is, it is on the longitudinal center line of said plate. An aperture 23 or other suitable non-skid means is provided adjacent the free end of the indicator to facilitate swinging member 14 relatively of plate 10, about pivot 13.

For releasably locking member 14 to plate 10 in any position of angular adjustment thereof there may be provided on indicator 20, intermediate the free end thereof and pivot 13, a slotted enlarged portion 25 through a curved slot 25 of which extends a threaded pin 26 which is secured to plate 10, the pin 26 having a nut 27 threaded thereon for clamping said member and plate together. The slot 25 is curved on a radius from pivot 13.

In the use of the invention described above as for checking the outside angle of a strip of ninety-degree angle-material, the nut 27 is loosened and the device is applied to the material, as indicated in chain-dotted lines in Figure 1, after which the nut may be tightened

to clamp plate 10 and member 14 together, the angle being directly readable on scale 22. Conversely, the angle may be first set on the scale and the parts clamped together so that an angle strip or other part may be worked or formed to a desired angle. Likewise the same settings may be utilized for checking or transposing an inside angle. Figure 3 illustrates the device as set for reading an inside angle of greater than ninety degrees (see chain-dotted lines), or an outside angle of the same number of degrees.

In Figures 4 and 5 is shown a protractor substantially like that shown in Figures 1 to 3, except that member 14a, corresponding to member 14, is made in two parts, the part 16a for the projecting straight-edged portion being pivoted to member 14a at 14b. A detent 30 is provided on part 16a, in spaced relation to pivot 14b, for releasable engagement in either one or other of two depressions 31 and 32 in member 14a, to retain said part either in an operative position thereof shown in chain-dotted lines in Figure 4 or in a retracted inoperative position, as shown in Figures 4 and 5. The operation of this modified form of the invention is otherwise the same as previously described, like parts being given like numerals with a suffix "a" except as otherwise noted.

Referring to Figure 6 there is illustrated another modified form of the invention, designed particularly for measuring inside angles. A plate 40 is of trapezoid shape providing one straight lateral side edge 41, the width and shape of the plate otherwise being as desired to measure within a desired range of degrees, as will be described. Pivoted at 42 at one corner of plate 40, closely adjacent edge 41, may be a quadrant-shaped plate or member 43, one straight edge 44 of which forms an outside angle with said edge 41. A narrow indicator or finger extends from plate 43, angularly of edge 41, to adjacent the other end of plate 40 and is provided with a mark 44a for indicating on a scale 45, similar to scale 22, the various degrees of angles between edges 41 and 44. The scale shown is designed to measure within a range of ninety degrees plus or minus fifteen degrees. For clamping the device at any desired angle, a pin in plate 40 extends through a slot 46, which is on a radius with pivot 42, said pin having a nut 47 threaded thereon and operable as previously described.

In Figure 7 is shown a protractor which is similar in all respects to that illustrated in Figures 1 and 2, except that plate 14 is rounded at 14c and 14d on a radius from pivot 13 equal to half the width of plate 14, so that bearing surface will be assured beyond the pivot ends of side edges 11 and 12 and in alignment therewith.

Thus has been provided a novel protractor which accomplishes the stated objects of the invention. Other modifications thereof may be resorted to without departing from the spirit of the invention or the scope of the appended claims.

What is claimed is:

1. A protractor comprising a plate providing opposite straight lateral side edges in parallelism, a member superposed on said plate and being pivoted thereto at a point substantially closely adjacent one end of the plate, said member having an outer straight edge portion longitudinally outwardly of said pivot to lie free and unobstructed beyond the pivot end of said plate and laterally across the same within a predetermined range of various angularly adjusted positions of said member on said pivot with respect to said plate, said outer straight edge portion of said

member extending in lateral direction from said pivot toward one of said straight lateral side edges of said plate but not beyond said side edge in any said angularly adjusted position of said plate and member and thereby defining a variable outside angle corner on the protractor for gauging inside angle corners, said member having an inner straight edge portion parallel to said outer straight edge portion thereof projecting beyond the other said straight lateral side edge of said plate and thereby forming therewith an inside angle corner which is variable correspondingly to the angles of said outside angle corner of the protractor for gauging outside angle corners, and means on said plate and member for indicating the angular variations of said inside and outside angle corners of the protractor, said pivot being equidistant from said lateral side edges of said plate, the edge portions at said one end of said plate being inwardly divergent from a point at a radius from said pivot.

2. A protractor comprising a plate providing opposite straight lateral side edges in parallelism, a member superposed on said plate and being pivoted thereto at a point substantially closely adjacent one end of the plate, said member having an outer straight edge portion longitudinally outwardly of said pivot to lie free and unobstructed beyond the pivot end of said plate and laterally across the same within a predetermined range of angularly adjusted positions of said member on said pivot with respect to said plate, said outer straight edge portion of said member extending in lateral direction from said pivot toward one of said straight lateral side edges of said plate but not beyond said side edge in any said angularly adjusted position of said plate and member and thereby defining a variable outside angle corner on the protractor for gauging inside angle corners, said member having an inner straight edge portion parallel to said outer straight edge portion thereof projecting beyond the other said straight lateral side edge of said plate and thereby forming therewith an inside angle corner which is variable correspondingly to the angles of said outside angle corner of the protractor for gauging outside angle corners, and means on said plate and member for indicating the angular variations of said inside and outside angle corners of the protractor, the edge portions of said one end of said plate being inwardly divergent from a point at a radius from said pivot, said pivot being equidistant from said lateral side edges of said plate, said member having arcuate portions on a radius from said pivot equal to half the distance between said side edges.

3. A protractor comprising a plate providing opposite straight lateral side edges in parallelism, a member superposed on said plate and being pivoted thereto at a point substantially closely adjacent one end of the plate, said member having an outer straight edge portion longitudinally outwardly of said pivot to lie free and unobstructed beyond the pivot end of said plate and laterally across the same within a predetermined range of various angularly adjusted positions of said member on said pivot with respect to said plate, said outer straight edge portion of said member extending in lateral direction from said pivot toward one of said straight lateral side edges of said plate but not beyond said side edge in any angularly adjusted position of said plate and member and thereby defining a variable outside angle corner on the protractor for gauging inside angle corners, said

member having an inner straight edge portion parallel to said outer straight edge portion thereof projecting beyond the other said straight lateral side edge of said plate and thereby forming therewith an inside angle corner which is variable correspondingly to the angles of said outside angle corner of the protractor for gauging outside angle corners, and means on said plate and member for indicating the angular variations of said inside and outside angle corners of the protractor, said inner straight edge portion of said member comprising a separate part pivoted to the member, releasable means being provided on said member and said separate part for selectively releasably retaining said separate part in outwardly projecting position or in inwardly folded position.

4. A protractor comprising a plate providing opposite straight lateral side edges in parallelism, a member superposed on said plate and being pivoted thereto at a point substantially closely adjacent one end of the plate, said member having an outer straight edge portion longitudinally outwardly of said pivot to lie free and unobstructed beyond the pivot end of said plate and laterally across the same within a predetermined range of various angularly adjusted positions of said member on said pivot with respect to said plate, and said outer straight edge portion of said member extending in lateral direction from said pivot toward one of said straight lateral side edges of said plate but not beyond said side edge in any angularly adjusted position of said plate and member and thereby defining a variable outside angle corner on the protractor for gauging

inside angle corners, said member having an inner straight edge portion parallel to said outer straight edge portion thereof projecting beyond the other said straight lateral side edge of said plate and thereby forming therewith an inside angle corner which is variable correspondingly to the angles of said outside angle corner of the protractor for gauging outside angle corner, and means on said plate and member for indicating the angular variations of said inside and outside angle corners of the protractor, said pivot being substantially centrally from said lateral side edges of said plate, the edge portions at said one end of said plate being inwardly divergent from a point at a radius from said pivot.
